EXTINGUISHING LIGHT METAL FIRES

Richard I. Thrune, Midland, Mich., assignor to
 The Dow Chemical Company, Midland, Mich., a
 corporation of Michigan

No Drawing. Application February 7, 1942,
 Serial No. 429,959

7 Claims. (Cl. 252—2)

This invention relates to a composition and method for extinguishing light metal fires.

The light metals, such as magnesium, aluminum, and their alloys, particularly when in the form of turnings, sawdust, or powder, are somewhat combustible, and, when ignited, as by careless handling, burn as an intense hot fire which is extremely difficult to bring under control. The ordinary fire-extinguishing fluids are worse than useless with such fires, since they are reactive chemically with the heated metal and frequently actually accelerate the combustion. Likewise, many common solid extinguishers are either dangerous to use with any but small metal fires or are relatively ineffective unless applied in enormous quantities. Certain proprietary extinguishers are available, but they are usually quite expensive, and in most cases liberate during use a considerable volume of choking or corrosive vapors. So far as is known, no fully satisfactory extinguisher has heretofore been developed.

It is, therefore, an object of the present invention to provide a composition and method for extinguishing light metal fires, which is non-hazardous, effective, inexpensive, and easy to apply.

This object is attained in the compositions of the invention which consist essentially of granular carbon, e. g., ground graphite, together with from about 0.5 to about 3 per cent by weight thereof of an at least semi-liquid high flash point organic substance unreactive chemically with the burning metal, such as a heavy mineral oil. In extinguishing a light metal fire, the mixture is applied to the burning metal, whereupon the graphite in the mixture covers the hot metal so as to exclude air therefrom and also conducts away the heat so rapidly that the temperature of the metal is soon reduced to below the ignition temperature. The small proportion of heavy oil or like substance evaporates slowly from the mixture, filling the interstices between the graphite particles with rising vapor, and thereby displacing air already present and preventing additional air from reaching the hot metal through the graphite.

The carbon in the extinguishing mixture may be present as any material which is composed principally of carbon and is substantially free of volatile materials, e. g., coke breeze, charcoal, or amorphous carbon powder. However, graphite, usually as ground graphitized foundry coke, is greatly to be preferred in the composition both because of its much higher ignition temperature

and its greater thermal conductivity. The carbon or graphite is ordinarily employed in granular form, and should preferably be sufficiently fine that the final mixture is free-flowing, and yet not so fine that packing or caking occurs. Optimum results are obtained with graded graphite powder which is all finer than 8 mesh (Tyler Standard screen scale), but at least 50 per cent of which is coarser than 200 mesh.

10 The minor constituent of the new composition may be any organic substance which has a high flash point and high boiling point, is at least semi-liquid at room temperature, and is substantially unreactive chemically with the burning metal to be extinguished. In general, oils having a flash point above 300° F. are preferred, especially the heavy hydrocarbon or mineral oils. However, various other high flash point oils including vegetable oils, such as cottonseed oil, 15 synthetic oily substances such as diphenyl oxide, and heavy liquids or semi-solids such as glycerine or low melting point coal-tar pitches, may also be used.

20 In the composition of the invention, the high flash point organic liquid or semi-liquid should be present in a proportion between about 0.5 and about 3 per cent by weight of the granular carbon. With proportions much below 0.5 per cent, the effectiveness of the composition is impaired. 25 whereas at percentages of liquid much above 3 percent the advantages of the invention are not retained. Minor proportions of other ingredients may, if desired, be added to the composition, but in general the simple compositions described are preferred.

30 In making the new extinguishers, the graphite or other carbon is ground to the desired degree of fineness and is then mixed with the minor proportion of high flash point liquid with such thoroughness that the liquid coats the individual particles of the ground graphite. With the heavier liquids and semi-liquids, hot mixing, as in a heated kneading machine, may be desirable.

35 In extinguishing a light metal fire, such as a pile of burning magnesium or magnesium-base alloy turnings or an incendiary bomb, the composition is merely sprinkled over the fire with a shovel so as to cover it uniformly. The heat of the fire is conducted away rapidly and air is excluded from the hot mass so that the blaze is quenched in a very short time. The quantity of the extinguishing composition necessary for any given fire depends, of course, upon the size and shape of the burning material. In general, however, there is required roughly one-third to an

equal amount of extinguisher by weight relative to the weight of the hot metal. The following example will illustrate the invention:

Example

Graphitized foundry coke was ground to a degree of fineness such that it was all finer than 8 mesh but more than 50 per cent was coarser than 200 mesh. This graphite was then mixed thoroughly at room temperature in a kneading machine with 2.0 per cent by weight of "Extra Hecla" mineral oil (a petroleum fraction having a specific gravity of 0.91, a flash point of 610° F., and a viscosity at 100° F. of 4600 seconds Saybolt). The resulting mixture was an effective extinguisher for magnesium fires.

The compositions of the invention possess a number of advantages which are not shared by other light metal fire extinguishers. The ingredients are cheap and easily compounded. The mixture is light in weight, stable, does not tend to absorb moisture from humid atmospheres, and remains free-flowing even after prolonged storage in open air. It is non-abrasive and non-reactive chemically with hot metal. Unburned portions of the metal are not destroyed or coated with residues which are difficult to remove, but can be recovered very readily. The extinguisher gives off little if any fumes and no corrosive vapors.

Because of the oil content, the composition is virtually non-dusting, even when sprinkled; yet the oil, being present only on the surface of the graphite particles, does not tend to run out of the composition on standing. When the extinguisher is applied to a metal fire, the heavy oil, as explained, evaporates slowly, the vapors so formed filling the space between graphite particles and excluding air from the fire. However, these vapors are present in such small amount that, although they are flammable, they do not form a sustained flame over the surface of the extinguisher which has been applied to the metal fire. A few scattered flashes may occur momentarily, but there are no continuous heat-producing flames which must be extinguished. As a result, the application of the new composition does not give rise to secondary fires which sometimes reignite the light metal while it is still hot and which always require attention in addition to the main metal fire.

This application is a continuation-in-part of prior application Serial No. 364,493, filed November 6, 1940.

What is claimed is:

5. A composition for extinguishing light metal fires which consists essentially of an intimate mixture of granular carbon together with from 0.5 to about 3 per cent by weight thereof of an at least semi-liquid high flash point organic substance unreactive chemically with the burning metal.
10. A composition according to claim 1 wherein the carbon is present in the form of graphite.
15. A composition according to claim 1 wherein the organic substance is an oil having a flash point above about 300° F.
20. A free-flowing substantially non-dusting composition for extinguishing light metal fires which consists essentially of granular graphite, the particles of which are coated with a mineral oil having a flash point above about 300° F., the oil being present in a proportion from between about 0.5 to about 3 per cent by weight of the graphite.
25. A composition according to claim 4 wherein the granular graphite is present as graded powder in which all the material has substantially a particle size finer than 8 mesh and at least 50 per cent of such material is coarser than 200 mesh.
30. 6. A method of extinguishing a light metal fire which comprises applying to the burning metal a composition consisting essentially of an intimate mixture of granular carbon together with from about 0.5 to about 3 per cent by weight thereof of an at least semi-liquid high flash point organic substance unreactive chemically with the burning metal.
35. 7. A method of extinguishing magnesium and magnesium alloy fires which comprises applying to the burning metal in a quantity sufficient to extinguish the fire a composition consisting essentially of granular graphite, the particles of which are coated with a mineral oil having a flash point above about 300° F., the oil being present in a proportion from between about 0.5 to about 3 per cent by weight of the graphite.

RICHARD I. THRUNE.
